UNITED STATES PATENT OFFICE.

MILLER H. HART, OF MARIETTA, OHIO.

RECEPTACLE-HOLDER.

No. 866,463.

Specification of Letters Patent.

Patented Sept. 17, 1907.

Application filed March 12, 1907. Serial No. 362,032.

To all whom it may concern:

Be it known that I, MILLER H. HART, a citizen of the United States of America, residing at Marietta, in the county of Washington and State of Ohio, have invented 5 certain new and useful Improvements in Receptacle Holders, of which the following is a specification, reference being had therein to the accompanying drawing.

This invention relates to receptacle holders, and the invention has for its object to provide a novel receptacle holder that can be suspended from a nail or hook 10 or supported upon a ledge.

My invention aims to provide a receptacle holder particularly designed for flower pots, the holder being constructed whereby it may be used in connection 15 with a window frame, and swung to any desired position, whereby a flower pot can be exposed to the sunlight or swung away from the window frame to prevent cold air entering the window from injuring a plant growing in a pot held by my improved holder. In this 20 connection my improved holder while designed for flower pots can be readily used for supporting vases, jars, and for such purposes it is designed to support a flower pot or vase at a window, where the ledge or sill of the window is not of sufficient width to accommodate flower pots. To this end, my improved holder is constructed of light and durable metal and provided 25 with a frame for embracing the receptacle, and with a drip basin for receiving water that may drip from the bottom of a flower pot. In connection with the holder 30 I can use a novel bracket for supporting the holder upon a window frame, whereby the holder can be swung outside of the window or a considerable distance upon the inside of the window, although the bracket is not necessary when it is desired to support the holder upon 35 a ledge or wall.

The detail construction entering into my invention will be hereinafter more fully described and then specifically pointed out in the appended claims, and referring to the drawing forming part of this specification 40 like numerals of reference designate corresponding parts throughout the several views, in which:

Figure 1 is a perspective view of my improved receptacle holder and bracket, Fig. 2 is an elevation of the holder as suspended from a wall or similar support, 45 Fig. 3 is a perspective view of the holder as supported upon a ledge or sill.

To put my invention into practice, I construct my improved receptacle holder of a light and durable piece of metal comprising a body portion 1, which is 50 stamped to provide a countersunk portion 2 serving functionally as a drip basin. The body portion 1 is provided with an outwardly extending tongue 3, which is bent upwardly to provide a standard 4. The standard 4 is provided with an inverted key-hole-

shaped opening 5 and the tongue 3 with a key-hole-shaped opening 6.

Secured to the base or body portion 1, and to the standard 4, is a basket or holding-frame 7, comprising side arms 8, a circular frame 9, and brace arms 8'. The circular frame 9 braces the side arms 8, the said basket 60 or holding-frame being preferably constructed of wire, the frame 9 being formed of one piece of wire bent into circular form and having its ends brought close together and projected through openings 11 provided therefor in the standard 4. Each side arm 8 is formed 65 from a single piece of wire which is doubled, the ends of the wire being secured in the base or body portion 1, the upper ends of the side arms 8 overlying and projecting beyond the circular frame 9. The brace arms 8' are connected at their lower ends in the base or body 70 portion 1, and at their upper ends are suitably connected to the circular frame 9, as by coiling the upper ends of said brace arms around the circular frame, as clearly seen in Fig. 3.

In Fig. 1 of the drawings, I have illustrated a novel 75 bracket 12 as being used to support my improved holder, said bracket having pivoted arms 14 and 15, the latter being provided with a hook 16 adapted to pass through the opening 5 of the standard 4 and support the holder in a horizontal position. As illustrated in dotted lines of Fig. 1, the holder can be swung outside of the window or swung away from the window whereby flowers supported within the holder can be exposed to the sunlight and in the night swung away 80 from the window to prevent the flowers from being chilled or otherwise injured by cold air. The bracket not only dispenses with the handling of a flower pot, in order to protect the flower growing therein, but permits of a flower pot being positioned in front of a window that could not otherwise support a flower pot if the 85 bracket were not used.

In Fig. 2 of the drawings, I have illustrated the holder as suspended from a nail or screw 17 fixed in a wall, it being possible to use the holder as a vase support in a compartment or use it upon the pillars or columns of a porch.

The holder is illustrated as supported from a ledge or sill in Fig. 3 of the drawings, the nail or screw 18 being used in connection with the opening 6 of the holder, and the head of the nail or screw retaining the holder in 100 a horizontal position.

From the foregoing description, it will be observed that the holder can be used in numerous ways and in numerous places for supporting flower pots, and while I have herein illustrated the holder as provided with 105 a drip basin, it is obvious that this basin can be readily dispensed with especially where the holder is simply used for vases and jardinières.

I do not care to confine myself to the size, proportion or minor details of construction entering into my invention, as various changes can be resorted to without departing from the spirit and scope of the invention as defined in the appended claims.

What I claim and desire to secure by Letters Patent, is:

1. In a receptacle holder, the combination with a bracket having pivoted arms, one of said arms having a hook, of a holder consisting of a body portion having a countersunk portion, a standard carried by said body portion and having an opening formed therein adapted to receive said hook, said body portion having an opening formed therein, a wire basket carried by said body portion and standard and consisting of side arms and a circular frame.
2. In a receptacle holder, a base or body portion having a tongue projecting therefrom in a plane with said base or body portion and provided with an opening, and a standard rising from the outer end of said tongue, and provided with an opening, substantially as described.
3. In a receptacle holder, a base or body portion having

a central depressed portion forming a drip pan, and having a projecting tongue provided with an opening, a standard rising from the outer end of the tongue and provided with an opening, and a wire basket secured to the base or body and to the standard.

4. In a receptacle holder, a base or body portion provided with a central depressed portion forming a drip pan, and having a tongue projecting from the body portion and provided with an opening, and a standard rising from the outer end of said tongue and provided with an opening, substantially as described.

5. In a flower pot holder, a base or body portion provided with a projecting tongue lying in a plane with said base or body portion and having an opening, a standard rising from the base or body portion and provided with an opening, and a basket mounted on the base or body portion and secured thereto and to the standard.

In testimony whereof I affix my signature in the presence of two witnesses.

MILLER H. HART.
